VERTICAL ROLLING MILL

John W. Sheperdson and Joseph M. O'Malley,
Worcester, Mass., assignors to Morgan Construction Company, Worcester, Mass., a corporation of Massachusetts

Application April 9, 1945, Serial No. 587,412

7 Claims. (Cl. 80—54)

1

This invention relates to vertical rolling mills, and more particularly to an improved construction and arrangement of apparatus for driving the rolls of comparatively large vertical mills.

It has been proposed heretofore to drive the rolls of vertical mills by means of gearing located in a pit beneath the rolls, and this construction has certain practical advantages. In the case of small mills it is feasible to assemble the driving mechanism into a complete unit before lowering the same into the pit. However, with large mills the driving mechanism is so heavy that it cannot be handled as an assembled unit by means of the equipment ordinarily available. For example, the assembled gearing for a vertical mill having rolls 28 inches in diameter may weigh approximately 195,000 pounds, whereas the capacity of the largest crane available for serving such a mill will seldom exceed 100,000 pounds. It therefore becomes necessary to complete the assembly of these larger driving mechanisms in the pit, and with prior constructions this is very difficult to accomplish in an expeditious and satisfactory manner. Furthermore, with certain prior driving mechanisms the various gears have not been properly supported to withstand the loads applied thereto, and in some cases it has been difficult to ensure accurate alignment of bearings and correct meshing of gears.

It is accordingly one object of the invention to provide a driving mechanism for vertical mills which can be readily installed in a pit beneath the rolls.

It is a further object of the invention to provide a driving mechanism for vertical mills, the said mechanism being located in a pit beneath the rolls and composed of readily separable components which can be handled one at a time by a crane of a capacity commonly installed for serving such mills.

It is a further object of the invention to provide a new and efficient arrangement of gearing for driving a vertical rolling mill, the construction being such as to avoid difficulties caused by misalignment of bearings, incorrect meshing of gears, or deflection of shafts.

With these and other objects in view, as will be apparent to those skilled in the art, the invention resides in the combination of parts set forth in the specification and covered by the claims appended hereto.

Referring to the drawings illustrating one embodiment of the invention and in which like reference numerals indicate like parts.

Fig. 1 is an elevation of a vertical rolling mill 55

2

and its driving mechanism, the latter being shown in section;

Fig. 2 is an elevation of the mill driving mechanism, showing a portion thereof being lowered into position;

Fig. 3 is an elevation similar to Fig. 2 but viewed from the right-hand side;

Fig. 4 is a section taken on the line 4—4 of Fig. 1; and

Fig. 5 is a section taken on the line 5—5 of Fig. 1.

The embodiment illustrated comprises a suitable roll housing 10 (Fig. 1) which is mounted on a supporting base 11. This base extends across a pit or opening 12 in the mill floor 14, the end portions of the base resting on foundation members or rails 15 at opposite sides of the pit. Two vertical rolls 16 are rotatably mounted in suitable bearings in the housing 10, and these rolls are driven by vertical spindles 18 which connect the lower ends of the rolls to a driving mechanism 19 located within the pit 12 and directly beneath the rolls.

This driving mechanism 19 comprises a pair of vertical gears or mill pinions 20 and 21 meshing with one another and provided with shafts 23 and 24 respectively which are supported above and beneath the gears in suitable antifriction bearings 25. These gears and bearings are mounted in a hollow casing or housing 27 which is formed of two flanged parts bolted together. These two parts are separable at the vertical plane defined by the axes of the gears. The upper ends of the gear shafts 23 and 24 are splined, fluted, or otherwise shaped to facilitate their connection to the roll spindles 18 by means of suitable coupling members 28.

The gear 20 is driven by bevel gear 30 located therebeneath and aligned therewith. This bevel gear is provided with a vertical shaft 31 which is supported near its upper end in an antifriction bearing 32 and near its lower end in an antifriction bearing 33. The bevel gear 30 is driven by a bevel pinion 35 located therebeneath and provided with a horizontal shaft 36. This shaft is supported near its inner end in an antifriction bearing 37 and near its outer end in an antifriction bearing 38. The bevel gear 30 and its driving pinion 35, together with their shafts and bearings, are mounted in a hollow casing or housing 40 which provides a support for the mill pinion housing 27, the latter being separable from the housing 40. The bevel gear housing 40 is constructed of three separable parts which are suitably flanged and bolted together, including a

lower member 41 and two upper members 42 and 43. The lower member 41 is formed with its upper surface in a horizontal plane at the height of the axis of the bevel pinion 35. The upper members 42 and 43 are separable at a vertical plane which passes through the axis of the bevel gear 30 and lies at right angles to the axis of the bevel pinion 35 (see Fig. 2). The housing member 43 is provided with an opening 45 above the outer bearing 38 of the bevel pinion shaft to permit inspection of the bevel gearing at the point of meshing engagement, this opening being closed by a removable plate 46. Preferably, the lower bearing 33 for the bevel gear shaft 31 and the inner bearing 37 for the bevel pinion shaft 36 are mounted in a bracket 47 which is supported within the lower housing member 41.

The bevel gear shaft 31 is connected to the gear shaft 23 thereabove to drive the same, and this connection is telescopic so that it may be completed by simply lowering the assembled pinion housing 27, with the pinions therein, into position on the top of the bevel gear housing 40. For this purpose the pinion shaft 23 is provided with a portion 49 which extends downwardly below the lower bearing 25, this extended portion being formed with a multiple spline or other non-circular cross section capable of transmitting the necessary torque. The pinion shaft 23 could be arranged to engage the bevel gear shaft 31 directly, but this would not be satisfactory unless substantially exact alignment could be provided and maintained between these shafts. As a practical matter this would be extremely difficult, since the shafts are mounted in separate bearings and in separate housings. Accordingly, the shafts are preferably connected by means of a vertical spindle 50 which is mounted within the interior of the shaft 31, the latter being of hollow construction. The upper end of the spindle 50 is provided with a socket 51 to receive the shaft extension 49 with a slight degree of looseness, this socket being of similar multiple spline or other non-circular cross section (see Fig. 4). The lower end of the spindle is flattened on opposite sides to provide a tongue 53 which fits within a similarly shaped opening 54 in the lower portion of the shaft. Thus the spindle forms a driving connection between the lower portion of the shaft 31 and the lower end of the shaft 23, this connection being such that extremely accurate alignment of the shafts is unnecessary for satisfactory operation. The weight of the spindle is carried by a flange 55 which extends outwardly from its upper end and rests on the upper end of the shaft 31.

It will now be apparent that before the roll housing 10 and its base 11 are installed, the lower member 41 of the bevel gear housing 40 will be placed on its foundation within the pit 12. Thereupon the bracket 47, the shaft 36, the bevel pinion 35, and the bearings 37 and 38 can be put into place. Next will follow the bearing 33 and the shaft 31, with the attached bevel gear 30. Thereupon the two upper members 42 and 43 of the housing can be installed, and the upper bearing 32 inserted. The spindle 50 can then be lowered into place to complete the assembling of the bevel gear drive unit. The mill pinion unit, including the pinion housing 27 with the two pinions 20-21 and their shafts and bearings, may be completely assembled in the shop or on the mill floor. This unit, when constructed for a 28 inch mill, will weigh approximately 52,000 pounds, which is well within the

capacity of cranes ordinarily provided to serve such mills. Accordingly the assembled mill pinion unit can be picked up by a crane sling and lowered into the pit 12, as shown in Figs. 2 and 3, until it rests in its proper place on the top of the bevel gear housing 40 and is securely bolted thereto. In the course of this lowering, the shaft extension 49 will enter the socket 51 to form a telescopic driving connection with the spindle 50.

In spite of the greatest of care in the manufacture and assembling of the parts, it will be found impossible to maintain perfect alignment between the shafts 23 and 31. However, this will cause no trouble in the operation, since the spindle 50 will readily accommodate itself to such misalignment as does occur, and torque will be transmitted smoothly and positively from the shaft 31 through the spindle to the shaft 23. It will be noted that each of the four gears is straddle-mounted, there being a separate pair of bearings for each gear, with the gear positioned between the bearings. This provides a very rugged construction which supports the gears in a rigid manner and ensures proper meshing engagement thereof.

Having thus described our invention, what we claim as new and desire to secure by Letters Patent is:

1. A driving mechanism for the two rolls of a vertical rolling mill comprising a bevel gear housing, a bevel gear mounted within the housing with its axis vertical, a bevel pinion mounted within the housing and meshing with the bevel gear to drive the same, a pinion housing separable from the bevel gear housing and supported on the top thereof, a pair of intermeshing vertical mill pinions mounted in the pinion housing and arranged to be connected at their upper ends to the respective mill rolls, one of the mill pinions being located directly above the bevel gear, and means providing a vertically slidable telescopic driving connection between the bevel gear and the mill pinion thereabove.

2. A driving mechanism for the two rolls of a vertical rolling mill comprising a bevel gear housing, a bevel gear mounted within the housing with its axis vertical, bearings for the gear both above and below the same, a bevel pinion mounted within the housing and meshing with the bevel gear to drive the same, a pinion housing separable from the bevel gear housing and supported on the top thereof, a pair of intermeshing vertical mill pinions mounted in the pinion housing and arranged to be connected at their upper ends to the respective mill rolls, one of the mill pinions being located directly above the bevel gear, bearings for each mill pinion both above and below the same, and means providing a vertically slidable telescopic driving connection between the bevel gear and the mill pinion thereabove.

3. A driving mechanism for the two rolls of a vertical rolling mill comprising a bevel gear housing, a bevel gear mounted within the housing with its axis vertical, bearings for the gear both above and below the same, a bevel pinion mounted within the housing and meshing with the bevel gear to drive the same, means rotatable with the bevel gear and providing an upwardly open socket of non-circular cross section, a pinion housing separable from the bevel gear housing and supported on the top thereof, a pair of intermeshing vertical mill pinions mounted in the pinion housing and arranged to be connected at their upper

ends to the respective mill rolls, bearings for each mill pinion both above and below the same, one of the mill pinions being located directly above the bevel gear, and a device of non-circular cross section extending downwardly from the said one mill pinion into telescopic engagement with the socket.

4. A driving mechanism for the two rolls of a vertical rolling mill comprising a bevel gear housing, a vertical shaft rotatably mounted in upper and lower bearings in the housing, a bevel gear on the shaft between the bearings, a bevel pinion mounted within the housing and meshing with the bevel gear to drive the same, a pinion housing separable from the bevel gear housing and supported on the top thereof, a pair of vertical shafts rotatably mounted in upper and lower bearings in the pinion housing and arranged to be connected at their upper ends to the respective mill rolls, one of the shafts of the said pair being located directly above the bevel gear shaft, intermeshing mill pinions mounted on the said pair of shafts between the bearings, and means providing a vertically slidable telescopic driving connection between the bevel gear shaft and the pinion shaft thereabove.

5. A driving mechanism for the two rolls of a vertical rolling mill comprising a bevel gear housing, a vertical shaft rotatably mounted in upper and lower bearings in the housing, a bevel gear on the shaft between the bearings, a bevel pinion mounted within the housing and meshing with the bevel gear to drive the same, a pinion housing separable from the bevel gear housing and supported on the top thereof, a pair of vertical shafts rotatably mounted in upper and lower bearings in the pinion housing and arranged to be connected at their upper ends to the respective mill rolls, one of the shafts of the said pair being located directly above the bevel gear shaft and having a downwardly projecting lower end portion of non-circular cross section, intermeshing mill pinions mounted on the said pair of shafts between the bearings, the upper end of the bevel gear shaft being hollow to receive the said downwardly projecting portion, and means rotatable with the bevel gear shaft providing an upwardly open socket of non-circular cross section in telescopic engagement with the said portion to drive the same.

6. A driving mechanism for the two rolls of a vertical rolling mill comprising a bevel gear housing, a vertical shaft rotatably mounted in upper and lower bearings in the housing, a bevel gear on the shaft between the bearings, a bevel pinion mounted within the housing and meshing with the bevel gear to drive the same, a pinion housing separable from the bevel gear housing and supported on the top thereof, a pair of vertical

shafts rotatably mounted in upper and lower bearings in the pinion housing and arranged to be connected at their upper ends to the respective mill rolls, one of the shafts of the said pair being located directly above the bevel gear shaft and having a downwardly projecting lower end portion of non-circular cross section, intermeshing mill pinions mounted on the said pair of shafts between the bearings, the bevel gear shaft being of hollow construction, and a vertical spindle mounted within the bevel gear shaft and having a driving connection at its lower end with the lower end of the bevel gear shaft, the spindle having an upwardly open socket of non-circular cross section in its upper end in telescopic engagement with the said downwardly extending portion to drive the same.

7. A driving mechanism for the two rolls of a vertical rolling mill comprising a bevel gear housing, a vertical shaft rotatably mounted in upper and lower bearings in the housing, a bevel gear on the shaft between the bearings, a bevel pinion mounted within the housing and meshing with the bevel gear to drive the same, a pinion housing separable from the bevel gear housing and supported on the top thereof, a pair of vertical shafts rotatably mounted in upper and lower bearings in the pinion housing and arranged to be connected at their upper ends to the respective mill rolls, one of the shafts of the said pair being located directly above the bevel gear shaft and having a downwardly projecting lower end portion of non-circular cross section, intermeshing mill pinions mounted on the said pair of shafts between the bearings, the bevel gear shaft being of hollow construction, and a vertical spindle mounted within the bevel gear shaft and having a driving connection at its lower end with the lower end of the bevel gear shaft, the spindle having an upwardly open socket in its upper end to receive the said downwardly projecting portion with a slight degree of looseness, the socket being of a similar non-circular cross section to provide a vertically slidable telescopic driving connection with the said downwardly projecting portion.
